UNITED STATES PATENT OFFICE

160,948

AIR CIRCULATOR UNIT

Jacob W. Kisling, St. Louis County, Mo.

Application October 13, 1949, Serial No. 5,474

Term of patent 14 years

(Cl. D26—7)

To all whom it may concern:

Be it known that I, Jacob W. Kisling, a citizen of the United States, residing in the county of St. Louis and State of Missouri, have invented a new, original, and ornamental Design for an Air Circulator Unit, of which the following is a specification, reference being had to the accompanying drawing, forming a part thereof.

In the drawing:

Fig. 1 is a top plan view of an air circulator unit, showing my new design;

Fig. 2 is a side elevational view, and

Fig. 3 is a fragmentary sectional view thereof taken on line 3—3 of Fig. 2.

The opposite side of the air circulator unit is the same as the side shown.

I claim:

The ornamental design for an air circulator unit, substantially as shown and described.

JACOB W. KISLING.
